PLANK FITTER TOOL

Original Filed March 3, 1930

Patented Oct. 25, 1932

1,885,087

UNITED STATES PATENT OFFICE

ARTHUR R. DE WITT, OF HARBOR SPRINGS, MICHIGAN, ASSIGNOR OF ONE-HALF TO
CARL L. WRIGHT, OF HARBOR SPRINGS, MICHIGAN

PLANK FITTER TOOL

Original application filed March 3, 1930, Serial No. 432,684, now Patent No. 1,828,103, dated October 20, 1931.
Divided and this application filed September 21, 1931. Serial No. 563,976.

The object of my invention is to provide a tool of simple, durable and comparatively inexpensive construction for use in fitting planks according to the method covered by my co-pending application, Serial No. 432,684, filed March 3, 1930, from which application the present application has been divided, Patent No. 1,828,103.

More particularly, it is my object to provide a cutting tool, whereby after a plank has been secured to the form of a boat and another plank is positioned adjacent thereto, such tool may be easily guided between the two planks for the purpose of cutting their adjacent edges parallel with each other, so that the planks can be consequently positioned in contact with each other for forming a tight well-fitting joint, such as is of great importance in marine construction.

Another object is to provide such a tool having a frame for carrying a cutter, a cutter, and a flexible guide means for guiding the cutter tool relative to a space between two planks.

Still another object is to provide a tool so constructed and arranged and provided with means that it may be employed for other operations on boat planks during the fitting of the planks to the frame, such as equalizing the grooves between deck planking for the reception of deck seam sealing compound, allowing the deck plank to be more carelessly fitted, both the joint between planks and between planks and covering boards.

With these and other objects in view, my invention consists in the construction, arrangement and combination of the various parts of my plank fitter tool, whereby the objects contemplated are attained, as herein-after more fully set forth, pointed out in my claims, and illustrated in the accompanying drawing, in which:

Figure 1 is a plan view of the tool used in fitting boat planks.

Figure 2 is a side elevation of the same.

Figure 3 is a sectional view on the line 3-3 of Figure 2.

Figure 4 is a sectional view through two planks of a boat showing them secured to a

rib of the frame of the boat and showing a gauge in use for spacing them apart.

Figure 5 is a similar view showing the cutter of the tool cutting between the two planks.

Figure 6 is a similar sectional view showing the planks fitted together at their adjacent edges and a batten secured in position on the planks.

Figure 7 is a sectional view through a plank showing the cutter tool in use for rabbeting the edge of the plank.

Figure 8 is a sectional view similar to Figure 6 showing a rabbeted plank in position adjacent another plank and secured thereto by a batten.

Figure 9 is a sectional view similar to Figure 7 showing the tool in operation for grooving the edge of the plank.

Figure 10 is a sectional view illustrating two of the planks shown in Figure 9 arranged edge to edge; and

Figure 11 is a perspective view of a depth gauge for the tool.

In the accompanying drawing, I have shown a form of tool embodying my invention. In the present instance, the tool is carried on the casing of an electric motor and is operated by the motor. I have used the reference numeral 10 to indicate generally the motor. The motor shaft is connected by a suitable gearing (not shown) with a drive shaft 14. The housing for the gearing is indicated at 16.

The shaft 14 carries the cutter tool 12. The motor casing is provided with a suitable handle 18 at its end opposite the cutter tool for convenience in manipulating the entire device. Other means might be provided for supplying power to the cutter tool, but since the tool must be portable, I find a small electric motor a satisfactory means for supplying such power.

Formed on or secured to the housing 16 is a frame 20, shown for instance in Figures 1 and 2, which has a portion projecting away from the motor and provided with a knob-like handle 22.

The operator in using the tool ordinarily

grasps the handle 18 at one end of the tool and the handle 22 at the other end.

The frame 20 carries a guard 24 extended over the upper part of the tool 12 for the protection of the user.

The tool is provided with a series of gauges which will now be explained.

The tool is provided with a depth gauge of which two forms are here illustrated.

10

Depth gauge

Referring to Figures 2 and 3, it will be seen that I have provided a depth gauge 26, which is V-shaped in longitudinal cross section with the obtuse angle down. A pair of angle brackets 28 are secured to the depth gauge 26 and extend upwardly therefrom. These brackets are provided with slots to receive the cap screws 30, which are screwed into the frame 20. The slots are vertically elongated and are not here shown, but are similar to those of the brackets 28a of the modified form of depth gauge 26a, which will be described below. One edge of the depth gauge 26 is arranged adjacent to the cutting tool 12, as shown for instance in Figures 3 and 7.

A slightly different type of depth gauge 26a is shown in Figure 11 and Figure 5. This gauge is similar in shape to that already described, but it is adjusted differently with relation to the tool 12, and has a slot 32 through which the tool 12 may project. The depth gauge 26a is secured to the frame 20 by means of brackets 28a, having the vertically elongated slots 28b to receive wing cap screws 30, similar to those already mentioned.

40

Front guide

At the forward part of the device, there is provided a front guide consisting of an upright bar 34 shown in Figures 1 and 2. The bar is provided at its lower part with a guide portion 36 and the guide shoulder 38. The guide bar 34 is mounted for up and down sliding movement on a bracket 42.

In use, the shoulder 38 of the guide bar 34 is normally held down against the material on which the tool is operated by means of a spring 40 secured to the upwardly projecting part of the guide 34 and to the bracket 42. The bracket 42 has a horizontal foot 43 in which is a laterally elongated slot 44, through which extends a wing cap screw 46 mounted in the frame 20. By means of this screw 46, the bracket is secured in any desired position of adjustment in a direction parallel with the drive shaft 14.

The guide bar 34 is provided with notches 48 (Figure 2) into which a pivoted pawl 50 (Figures 1 and 2) may be swung for holding the guide in a raised position or a lowered position.

Trailing guide

The apparatus is also provided with a trailing guide to be made and hung the same as the front guide, excepting that the spur engaging the seam must be slightly less in thickness than the cutter tool, so as to slide freely through the saw cut. Both front and rear guides should be equipped with a pivoted pawl or a spring or the like, which would snap into a notch in the side of the guide bar when either raised or lowered into extreme positions. The trailing or rear guide has the vertically slidable bar 52 with the guide portion 53 and shoulder 54 similar to the corresponding parts of the front guide. The trailing guide has a spring 42 and a pawl 50 and a notch, not shown, like the notch 48.

It will be seen from the foregoing description that the guide bars 34 and 52 may be conveniently adjusted laterally for accommodating them for use with cutting tools 12 of different thicknesses and also for adjustment to proper positions for cooperating with the material on which the tool is to be used.

Rabbet gauge

A rabbet gauge or fence 58 (Figures 1 and 2) is also provided. Extending upwardly from the gauge 58 adjacent the respective ends thereof are the arms 60, having at their upper parts the enlarged portions 62 (see Figures 1, 2 and 3) to receive the rods 64 projecting laterally from the frame 20.

The wing set screws 66 are mounted in the enlarged hub-like portions 62 for locking the arms 60 to the rods 64 for thus securing the gauge 58 in various laterally adjusted positions with relations to the rods 64 and the cutting tool. The lower edge of the rabbet guide 103 is curved on part of an ellipse to provide greater adaptability in rabbeting or sawing curved or irregular work. It may be mentioned that the rods 64 are preferably slideable in the frame 20 for adjustment, and are locked in various positions of adjustment by means of twin set screws 67.

My method of fitting planks to the frames of boats with my improved tool involves fastening a plank 68 to the frame. A rib of the frame of the boat is indicated at 70 in Figures 4, 5 and 6. I then fasten another plank 72 temporarily in place adjacent to the plank 68. Clamps 74 may be employed for this purpose.

A gauge 75 is preferably employed for positioning the closest adjacent portions of the planks 68 and 72 a predetermined distance apart. It will, of course, be understood that where necessary the planks are steamed and brought to the proper shape before being secured and clamped to the boat frame in order that they may properly follow the irregular contour of the boat.

Normally the next operation, as illustrated

in Figure 5, is to pass a cutting tool 12 of a selected thickness between the planks 68 and 72 from one end to the other, so that the adjacent edges of the planks will then be parallel with each other and will snugly fit together.

The front and trailing guides are, of course, properly set for guiding the cutting tool with relation to the edge of one plank.

10 At the stem of the boat, where it is not desired to cut through the stem post, the front end of the fitting tool may be rested on the plank, and then the rear end tipped downwardly until the tool cuts into the plank, and 15 the depth gauge 26a engages both planks.

When the front end of the fitting tool is first positioned for this operation, the front guide bar 34 will be in a raised position as indicated by dotted lines in Figure 2.

20 The depth gauge 26a serves to provide a firm bearing on both planks and to prevent any side twisting of the cutting tool.

After the cutting tool has been run lengthwise between the planks 68 and 72, the clamps 25 may be loosened and the plank drawn to tight position against the fixed plank.

By the use of my tool, it is found that the contacting edges of the two planks fit perfectly for their entire lengths and no further 30 cutting for fitting need be done in order to obtain a tight joint. If desired, a batten 76 may be glued and suitably fastened over the seam between the planks 68 and 72 as illustrated in Figure 6.

35 In boat construction, where sawed ribs are used, the frame may be set up and the battens fastened to the ribs in notches sawed into the ribs, so that the battens will be flush with the outer faces of the ribs and then the plank 40 may be fastened to the ribs and the battens.

When a plank is fitted adjacent to the keel 78 of the boat, the depth gauge 26 is used instead of the depth gauge 26a, wherever the keel is thicker than the plank, because the 45 left half for instance of the gauge 26a would be interfered with by the keel, which is shown by dotted lines in Figure 5.

In Figure 8, there is illustrated a joint, which is preferable in some instances. In that 50 type of joint, a rabbet 80 is formed in the edge of the plank 72 for example for the reception of a sealing compound 82, such for instance as is described in my Letters Patent, No. 1,805,812, issued May 19, 1931. For forming this rabbet, the depth gauge 26 and the rabbeting gauge 58 are used, as illustrated in Figure 7.

For making this use of the tool, the plank is placed on a work bench or the like.

55 Another type of boat seam is illustrated in Figure 10. There I have shown rabbets 84 formed in the adjacent edges of the planks 68 and 62 and partially filled with a compound 82 forced into the seam through an opening 86 in a batten or the like 87 as de-

scribed in my patent above referred to. The rabbets 84 may be formed by using the tool as illustrated in Figure 7 and by properly adjusting the depth gauge and the rabbet guide.

It is obvious that my tool may be used for forming other types of rabbets and grooves and for doing various work involved in connection with the fitting of planks to boat frames.

75 In Figure 9, I have shown the tool with the parts adjusted to cut a groove in the edge of a plank 68.

80 My tool and the method employed with it are adapted to eliminate a great deal of skilled hand work formerly necessary for fitting planks to boat frames. Heretofore it has been common to saw the boat planks from straight planks according to a pattern previously drawn. This is usually done on a band saw because the planks are usually curved and are wider at some points in their length than at other points. When this old method is used, it is found that when the planks are put together on the frame, their adjacent 85 edges are not parallel, and it has therefore been necessary to do a lot of marking and removing of the planks from the boat frame, the planing of the marked edges, refitting and replaning in order to get the joints to properly fit together. Nearly every time the planks are put on the boat frame, they must be steamed to make them follow the contour 90 of the frame. All of this has required much time and has made necessary the service of 95 highly skilled men.

100 Where my tool is employed in the manner hereinbefore described, it is a simple matter to fasten the plank 68, then clamp the plank 72 spaced from the plank 68 by means of the gauge 75. This gauge is of slightly greater width than the guide ends 36 of the front guide bar 34. The cutting tool is then passed between the planks and thereupon the adjacent edges are exactly parallel,—no difference 105 what variation there may have been in the edges prior to this operation.

110 The plank can then be placed together to form a tight joint and battens may be moved and fastened into position or caulking material or compound may be used for filling the seam.

115 The guide 34 and the guide 52, which is thicker than the guide portion 36 of the guide 120 34 and is aligned therewith are so constructed and arranged as to cause the tool when properly used to follow the space between the planks accurately. The depth gauge 26 or 26a as the case may be regulates the depth of the cut, so that the saw will not cut into the ribs 70, but will cut clear through the planks.

125 Where I use the term "plank" in my claims, it will be understood that I intend to refer to any member on which the tool may be properly used.

Too much emphasis cannot be placed upon the flexibility and adaptability of the tool for boat building. Its small cutter, compactness and its movable front and rear guides contribute to these advantages.

In the plank fitter tool, the guides must be very short lengthwise of the tool and set close to the saw to permit the tool to follow the irregular shape sidewise of the planking joint.

10 Since the tool may have to be run over a concaved surface at one point in a seam and further along it may be convexed, a flat depth gauge cannot be used and neither can a stationary guide ahead of the saw. So I 15 have designed a spring guide which permits flexibility with a spur at the bottom of the guide in the seam with the shoe acting as a depth gauge on the guide and running on the surface of the work.

20 This tool is so constructed as to follow irregular shaped lines both up and down and sidewise, as will be found in the lines of a boat. The spring guide is also to be set at an offset with the saw and not in line as in 25 other devices.

Both the spring guide and the rear guide are to be used as a lateral guide and held tight to the edge of the plank already fastened. The spring guide should be set with just 30 enough offset with saw to permit the saw to trim the edge of the fixed plank, cutting the bevel to correspond with the one which is cut on the plank that is clamped on. In the plank fitter, the rear guide is a very narrow 35 guide set very close to the saw, permitting the saw to be run in an irregular course.

The lateral guide is of elliptical shape to permit sawing or rabbeting the edge of the irregular shaped work, as there is very little 40 straight work in boat hull construction.

Changes may be made in the construction and arrangement of the parts of the fitting tool without departing from the real spirit and purpose of my invention, and it is my 45 purpose to cover by my claims, any variations in the size, shape, material or arrangement of the parts or any use of mechanical equivalents, which may be reasonably included within their scope.

50 I claim as my invention:

1. A plank fitter tool comprising a frame, a cutter carried thereby, a laterally adjustable guide in advance of said cutter of less thickness than the cutter, and a laterally adjustable guide behind said cutter of less thickness than the cutter.

2. A plank fitter tool comprising a frame, a cutter carried thereby, a laterally adjustable guide in advance of said cutter of less thickness than the cutter, and a laterally adjustable vertically yieldable guide behind said cutter of less thickness than the cutter.

3. A plank fitter tool comprising a frame, a cutter carried thereby, a laterally adjustable vertically spring-tensioned guide in ad-

vance of said cutter of less thickness than the cutter, and a guide behind said cutter of less thickness than the cutter.

4. A plank fitter tool comprising a frame, a cutter carried thereby, a laterally adjustable guide in advance of said cutter of less thickness than the cutter, and a laterally adjustable guide behind said cutter, one of said guides being vertically spring-tensioned.

5. A plank fitter tool comprising a frame, a cutter carried thereby, a vertically yieldable guide in advance of said cutter of less thickness than the cutter, and a guide behind said cutter, whereby said tool is adaptable for work on other than flat surfaces.

6. A plank fitter tool comprising a frame, a cutter carried thereby, an adjustable spring tensioned guide in advance of said cutter, a depth gauge for said cutter, V-shaped in lengthwise cross section, and an adjustable spring tensioned guide behind said cutter.

7. A plank fitter tool comprising a frame, a cutter carried thereby, a guide close to said cutter of less thickness than the cutter and relatively short from front to rear to permit it to follow a lateral curve mounted for sliding adjustment, and yielding means for holding said guide at the lower limit of its movement.

8. A plank fitter tool comprising a frame, a cutter carried thereby, a guide in advance of said cutter close to the cutter, spring means to hold said guide down and a shoulder on said guide to engage material being cut and thereby limit downward movement of the guide, said guide being laterally adjustable and relatively short from front to rear, and a guide close behind the cutter to permit the cutter to follow a lateral curve.

9. A plank fitter tool comprising a frame, a cutter carried thereby, a vertically yieldable guide in advance of said cutter of less thickness than the cutter, a guide behind said cutter, whereby said tool is adaptable for work on other than flat surfaces, and means to latch the guides in certain positions, against yielding movement.

10. A plank fitter tool comprising a frame, a cutter carried thereby, a depth gauge for said cutter V-shaped in cross section and a lateral gauge therefor for use during rabbeting and grooving operations of the fitter tool, with its lower edge curved on part of an ellipse.

11. In a plank fitter tool of the kind described, a frame, a cutter mounted thereon, a portable power plant operatively connected with said cutter and supported on said frame, a guide carried by said frame in front of the cutter, having a guide portion of less thickness than the cutter, a guide of less thickness than the cutter supported on said frame rearwardly of said cutter, and means for adjusting said guides laterally with relation to the cutter.

12. In a plank fitter tool of the kind described, a frame, a cutter mounted thereon, a portable power plant operatively connected with said cutter and supported on said frame, a guide of less thickness than the cutter carried by said frame in front of the cutter, a guide of less thickness than the cutter supported on said frame rearwardly of said cutter, means for adjusting said guides laterally with relation to the cutter, and a depth guide carried by said frame.

13. In a plank fitter tool of the kind described, a frame, a cutter mounted thereon, a portable power plant operatively connected with said cutter and supported on said frame, a guide of less thickness than the cutter carried by said frame in front of the cutter, a guide of less thickness than the cutter supported on said frame rearwardly of said cutter, means for adjusting said guides laterally with relation to the cutter, and a depth guide carried by said frame V-shaped in longitudinal cross section and mounted for up and down adjustment on the frame.

14. In a plank fitter tool of the kind described, a frame, a cutter mounted thereon, a portable power plant operatively connected with said cutter and supported on said frame, a guide of less thickness than the cutter carried by said frame in front of the cutter, a guide of less thickness than the cutter supported on said frame rearwardly of said cutter, means for adjusting said guides laterally with relation to the cutter, a depth guide carried by said frame, and a rabbet guide carried by said frame and mounted for up and down lateral adjustment with relation to the frame and the cutter.

15. A plank fitter tool comprising a frame, a cutter carried thereby and a gauge having a V-shaped lower face adapted to serve as a depth gauge for following convex or concave curves and yieldable guides, arranged before and behind the cutter.

45 Des Moines, Iowa, August 31, 1931.
